EXPANDING BORING HEAD

Ole Severson, Shelton, Conn., assignor to The
O. K. Tool Company, Inc., New York, N. Y., a
corporation of New York

Application September 22, 1931, Serial No. 564,292

6 Claims. (Cl. 77—58)

This invention is concerned with rotary cutting tools, and specifically rotary cutting tools of the type having removable and adjustable blades.

In the interests of rigidity and simplicity a solid cutter tool with integral cutting blades would be desirable. However, there are other important desiderata which must be taken into account in the achievement of a practical tool, among which may be noted as initial factors the 10 longevity and tool cost over a period of time; and the expediency of providing a supporting body and cutting edges of material adapted, respectively, to the functions to be performed.

Accordingly, constructions have been developed 15 in which the blades are removable whereby they may be made of special materials and readily replaceable upon having become worn. As more extended developments in this direction various constructions have provided means for adjusting 20 the blades to prolong their life and maintain the size of the assembled cutter tool.

The present invention is directed to the accomplishment of these advantages of blade adjustment, and at the same time a cutter tool possessing 25 the rigidity and strength of a solid cutter. A primary feature of construction promoting such rigidity is the provision of an arrangement whereby, in the assembled cutter, opposed cutter blades are not only locked in the cutter body but 30 are also clamped together whereby the blades are, in effect, integral and constitute the cutter proper thereby eliminating the variations resulting from mis-alignment or disturbance of individual blades independently mounted in the cutter.

An important feature is the ease and rapidity 35 with which the cutter blades may be adjusted. To adjust the blades requires but the manipulation of a single clamping screw, and of a screw threaded adjusting collar which collar in its advancement serves to simultaneously advance all 40 the blades. Because of this facility of adjustment, and also because of the exceptional accuracy and fineness with which adjustments may be made, the construction is particularly adaptable to boring tools, a necessary characteristic 45 of which is the maintenance of a particular diameter, coupled with the ability to selectively change the diameter in accordance with the size of the opening desired in particular cases.

50 Other objects and advantages will be in part indicated in the following description and in part rendered apparent therefrom in connection with the annexed drawing.

To enable others skilled in the art so fully to 55 apprehend the underlying features hereof that

they may embody the same in the various ways contemplated by this invention, a drawing depicting a preferred typical construction has been annexed as a part of this disclosure and, in such drawing, like characters of reference denote 60 corresponding parts throughout all the views, of which:—

Figure 1 is a view in elevation of the complete cutter shown partially in section in order better to disclose certain details. Fig. 2 is a view of the 65 lower end of the cutter similar to Fig. 1 but with the exterior unbroken. Fig. 3 is a view similar to Fig. 2 but with the cutter rotated 90° therefrom. Fig. 4 is a plan view of the lower end. Fig. 5 shows an individual blade in elevation; and Fig. 6 is a lower end view of one of these blades. 70

The invention is shown applied to a boring tool for which it is particularly adapted. The tool may include any conventional means for mounting in a machine, such as the shank 10 having an opening 11 in which the upper end portion 12 of the cutter body 13 may be threaded. The lower end of the body 13 is formed with an enlarged forked portion 14 resulting in a slot 15 in which are mounted the opposed complementary 75 blades 16 and 17.

The blades 16 and 17 are provided with overlapping portions 18 and 19 respectively having interfitting serrations 18a and 19a on the adjacent surfaces, the serrations extending at right angles to the cutter axis whereby the blades are capable of radial adjustment relative to each other but are otherwise maintained in close alignment. The inner edges of the blades are cut away leaving inclined cam surfaces 20 and 21 respectively. 85

The lower end of the sides of the fork 14 are connected by a screw bolt 22 upon which is mounted a roller 23 located in the slot 15. The cam surfaces 20 and 21 are adapted to simultaneously bear on opposite sides of this roller. 95

The cutter body 13 is provided with a threaded portion 24 upon which is threaded a collar 25. A bearing ring 26 is located between the collar 25 and the upper ends of the blades 16 and 17. A set screw 27 projecting into the key-way 28 prevents the ring 26 from turning. The threaded collar 25 is provided with suitable graduations 29 to indicate the degree of adjustment. 100

Advancement of the blades, it will be noted, is 105 accomplished through the rotation of the collar 25 in a direction to advance it toward the lower end, engagement of the blades 16 and 17 thereby, through the bearing ring 26 forces the blades into engagement with the roller 23. The action 110

of the inclined surfaces 20 and 21 is then to spread the blades radially outward. When the desired adjustment has been accomplished the screw bolt 22 is tightened and the blades 16 and 5 17 thereby rigidly clamped in the cutter body.

Through the medium of the serrations on the opposed surfaces of the blades 16 and 17 the blades are simultaneously locked together and in effect are integral. The provision of the roller abutment 23 renders the blades self-aligning in the cutter tool the blades freely and quickly assuming a symmetrical balanced position in the cutter. As a net result the two blades cooperate as a unitary member and any such variation 10 in the diameter, or in the position of the blades, of the cutter under the strain of cutting operations, as is frequently the case where the blades are independently mounted, is eliminated.

Adjustment of the blades is very readily accomplished requiring merely the loosening of the screw bolt 22; the advancement of the collar 25; and retightening of the screw bolt 22. Normally the screw bolt 22 is turned initially in the loosening direction but a small amount, whereby the blades are released from rigid clamping sufficient 25 to enable the collar 25 to force them outwardly; but not rendered entirely free or loose. In some cases for very fine adjustment it may even be unnecessary to loosen the screw bolt at all.

Without further analysis the foregoing will so fully reveal the gist of this invention that others can, by applying current knowledge, readily adapt it for various utilizations by retaining one or more of the features that, from the standpoint 30 of the prior art, fairly constitute essential characteristics of either the generic or specific aspects of this invention and, therefore, such adaptations should be, and are intended to be, comprehended within the meaning and range of equivalency of the appended claims.

Accordingly I claim as new and desire to secure the following combinations and elements, or equivalents thereof, by Letters Patent of United States:—

45 1. A rotary cutter tool combining a body member having a slot therein extending axially thereof; opposed complementary blades disposed in said slot having overlapping portions, the adjacent surfaces of said portions being provided with interfitting formations extending transversely of said cutter axis and permitting independent radial movement of said blades; collar means threaded on said body member adapted to simultaneously engage an end of said blades to move the latter axially of said member; a screw bolt 50 extending through and connecting the sides of said slot for clamping the blades therein; and a roller on said bolt disposed in said slot, said blades being provided with opposed inclined cam surfaces engaging said roller on opposite sides thereof whereby axial movement of said blades adjusts the blades radially.

60 2. A rotary cutter tool combining a body member having a forked end extending axially thereof; a pair of complementary blades located between the sides of said fork; complementary serrations on the adjacent surfaces of said blades extending at right angles to the axis of said cutter; a clamping bolt extending through the outer 65 ends of said fork; a roller carried thereby located between the sides of said fork; collar means threaded on said body member adapted to engage the inner ends of said blades, the blades being provided with inclined cam surfaces engaging 70 said roller on opposite sides thereof

whereby outward advancement of said collar serves to radially advance said blades and said screw providing a means to permit said clamping bolt to be turned thereby to clamp said blades between the sides of said forked end.

80 3. A rotary cutter tool combining a bifurcated body member having a slot therein extending inwardly from the free end thereof and axially of said body member; a pair of complementary overlapping blades located in said slot and having cutting portions projecting beyond the end of said body member; interfitting formations of the adjacent surfaces of said blades extending transversely to the axis of said cutter; threaded means for engaging said blades to adjust the latter axially of said body member; a draw bolt connecting spaced walls of said bifurcated body member for contracting said walls and clamping the blades in said slot, said bolt being located forwardly of the point of overlap of said blades; and an abutment carried by said bolt, said blades being provided with opposed inclined cam surfaces adapted to simultaneously engage said abutment on opposite sides thereof whereby adjustment of said blades axially by said threaded means serves simultaneously to adjust said blades radially.

85 4. A rotary cutter tool combining a body member having a slot therein extending inwardly from the free end and axially thereof; opposed complementary blades disposed in said slot having overlapping portions, the adjacent surfaces of said portions being provided with interfitting formations extending transversely of said cutter axis and permitting independent radial movement of said blades, said blades also having cutting portions projecting beyond the free end of said body member; collar means threaded on said body member adapted to simultaneously engage an end of said blades to move the latter axially of said member; an abutment roller disposed in said slot, 90 said blades being provided with inclined cam surfaces engaging said abutment roller whereby adjustment of said collar means serves to also adjust said blades radially; and means for drawing together the sides of said slot to clamp said blades in said slot.

95 5. A rotary cutter tool combining a bifurcated body member having a plane walled slot therein extending inwardly from one end thereof and axially of said body member; a pair of complementary overlapping blades located in said slot and having cutting portions projecting beyond the end of said body member; a plurality of parallel interfitting formations on the adjacent surfaces of said blades extending transversely to the longitudinal axis of 100 said tool; threaded means for engaging said blades to adjust them axially of said body member; a draw bolt connecting the spaced walls of said bifurcated body member and adapted to contract said walls and thereby clamp the blades in 105 said slot, said bolt being located forwardly of the point of overlap of said blades; and an abutment carried by said bolt, said blades being provided with opposed inclined cam surfaces adapted simultaneously to engage said abutment on opposite sides thereof whereby adjustment of said blades axially by said threaded means serves simultaneously to adjust said blades radially.

110 6. An expandable rotary boring tool combining a substantially cylindrical body member having a slot providing flat parallel walls extending inwardly from the end thereof; a blade assembly comprising a pair of opposed complementary blades fitting the walls of said slot, said blades having overlapping portions and cutting portions pro-

jecting radially from said overlapping portions and extending forwardly beyond the end of the body member, the adjacent surfaces of said overlapping portions being provided with interfitting 5 serrations extending at right angles to the axis of said tool; means for simultaneously adjusting

said blades radially and axially of said body member and forming positive abutments for preventing inward movement of said blades from selected adjusted positions; and means for clamping said blades together and to the walls of said slot.
